UNITED STATES PATENT OFFICE.

WILLIAM MABLE, OF FORT COLLINS, COLORADO, ASSIGNOR OF ONE-HALF TO WINTHROP B. MORRIS, OF FORT COLLINS, COLORADO.

TRAVELING-CASE.

No. 885,853.

Specification of Letters Patent. Patented April 28, 1908.

Application filed October 9, 1907. Serial No. 396,687.

To all whom it may concern:

Be it known that I, WILLIAM MABLE, a citizen of the United States, residing at Fort Collins, in the county of Larimer and State 5 of Colorado, have invented a new and useful Traveling-Case, of which the following is a specification.

This invention relates to traveling cases and its object is to provide a combined suit 10 case and telescope which can be readily adjusted so as to hold a greater or less number of articles as may be desired, said adjustment being readily effected and the parts firmly secured against movement subsequent to 15 their adjustment.

A still further object is to provide a device of this character having a cover which can be opened or closed independently of the relative positions to which the adjustable 20 portions of the case have been shifted.

With these and other objects in view the invention consists of certain novel features of construction and combinations of parts which will be hereinafter more fully described 25 and pointed out in the claim.

In the accompanying drawings is shown the preferred form of the invention.

In said drawings: Figure 1 is a perspective view of a case embodying the present invention. Fig. 2 is a transverse section therethrough. Fig. 3 is a longitudinal section through a portion of the cover and showing the means for detachably fastening the handle thereto. Fig. 4 is an enlarged section through one of the clamping devices for holding the adjustable section against independent movement.

Referring to the figures by characters of reference, 1 designates the bottom section of 40 the case, the same being preferably in the form of a rectangular receptacle having feet 2 secured transversely upon the bottom thereof and provided with slotted guide strips 3 which are riveted or otherwise fastened to the sides of the section 1. The inner 45 portion of the walls of these slots are rabbeted as indicated at 4 to constitute guides and retainers for buttons 5 designed to slide within the rabbeted portions of the strips 3 and having screw threaded stems 6 extending 50 therefrom and through the slots. Surrounding and slidably mounted on the bottom section 1 is an adjustable section 7 de-

signed to normally rest upon the projecting ends 8 of the cross strips 2. The bottom of 55 this adjustable section is of course open, the section 1 constituting a closure therefor. The top of the section 7, however, has a cover 9 hinged thereto as at 10 and provided with suitable locks 11 whereby it can be held in 60 closed position. Secured upon the sides of the adjustable section 7 close to the lower edges thereof are washers 12 each of which has an opening 13 therethrough designed to receive one of the stems 6 hereinbefore referred to. Small thumb pieces 14 are preferably screwed upon the outer end portions of the stems so that when said thumb pieces are rotated they bind the adjustable section 7 in any position to which it may be shifted 70 upon the section 1. A handle 15 is provided at its ends with rings 15^a designed to engage snap hooks 16 which are fastened to the middle portion of the cover 9 by means of bolts 17 extending through apertures within said 75 cover.

When the parts are arranged in the manner described the device is designed to be used as a telescope and by loosening the thumb pieces 14 section 7 can be adjusted upwardly 80 or downwardly, the heads or buttons 5 sliding within the strips 3 during this movement. When the desired adjustment has been effected the thumb pieces are rotated so as to produce the binding action heretofore described whereupon the two sections 1 and 7 become securely fastened together. Should it be desired to use the device as a suit 85 case the section 7 is moved into position against the projecting ends 8 of the strips 2 and the two sections are then bound together in the manner described. Handle 15 is detached from the snap hooks 16 and is fastened to similar snap hooks 18 on one side 90 of section 7.

It will be seen that this device is very simple, durable, and efficient and that it combines all the features of a telescope and suit case.

What I claim is:

A traveling case comprising telescopically connected body and top sections, longitudinally slotted guide strips secured upon the sides of the body section, said strips having inturned ends extending under the bottom 105 of the body, feet outstanding from the strips

adjacent said ends, a button slidably mounted within each guide strip, means extending therefrom for engaging the top section, and clamping means engaging said extending 5 means for binding the top section upon the guide strips, said feet constituting abutments for the top section, and a handle upon the top section.

In testimony that I claim the foregoing as my own, I have hereto affixed my signature 10 in the presence of two witnesses.

WILLIAM MABLE.
